CLAIM

The ornamental design for a sound intensifying receiver, as shown.

DESCRIPTION

FIG. 1 is a front elevational view of a sound intensifying receiver showing my new design;

FIG. 2 is a rear elevational view thereof;

FIG. 3 is a top plan view thereof;

FIG. 4 is a bottom view thereof; and,

FIG. 5 is a side elevational view thereof as viewed from the right side of FIG. 1.
